UNITED STATES PATENT OFFICE.

ALFRED FRENETTE, OF THETFORD MINES, QUEBEC, CANADA.

RAZOR-HONING IMPLEMENT.

1,257,692.

Specification of Letters Patent. Patented Feb. 26, 1918.

Application filed January 31, 1917. Serial No. 145,756.

To all whom it may concern:

Be it known that I, ALFRED FRENETTE, a subject of the King of Great Britain, residing at Thetford Mines, in the Province of Quebec and Dominion of Canada, have invented certain new and useful Improvements 5 in Razor-Honing Implements, of which the following is a specification.

This invention relates to a razor honing implement and the primary object is to provide a device for facilitating the proper motion imparted to a razor when the same is being sharpened so that an even and uniform pressure will be applied to the blade 10 while it is being moved across the hone.

Another object of the invention is the provision of a razor honing implement having a clip adapted to receive a reciprocatory motion and pivotally mounted whereby the 20 "sweep" or length of the arc through which the razor is moved may be varied according to the length of the hone employed.

As another object of the invention the device includes the provision of resilient means 25 associated with the pivot connection of the swinging clip whereby an even pressure may be maintained upon the edge of the razor blade when the latter is in contact with the surface of the hone.

30 A further object of the invention is to provide means for fastening the hone at any desired angle upon the supporting base.

A further object of this invention is the provision of a razor honing implement 35 which consists of comparatively few parts and is simple in construction, but durable and well adapted to withstand the rough usage to which devices of this character are ordinarily subjected.

40 For a full description of the invention and the advantages and merits thereof, reference is to be had to the following description and the accompanying drawings, wherein is illustrated the preferred form of my 45 invention, in which:

Figure 1 is a plan view, the razor being shown in diagram.

Fig. 2 is a vertical transverse section the razor being removed.

50 Referring to the drawing, wherein is illustrated the preferred form of my invention, and in which like numerals of reference indicate corresponding parts throughout the several views, the supporting plate

55 1 is of substantially rectangular formation and includes a projection 2 extending from

the rear edge of the supporting plate. The upper surface of the supporting plate 1 is of a size sufficient to conveniently receive an ordinary razor hone designated by the character A. For retaining the hone in proper position upon the supporting base, I have provided a pair of retaining elements 3 each of which is adapted to contact with one longitudinal edge of the hone. Each retaining 60 element consists of a relatively long strip 4 engaging the edge of the hone while intermediate the ends of the strip 4 the same is integrally connected to a flange 5 through which a fastening screw 6 is projected and 65 extended into the base 1 for securely holding the retaining elements. At each end of the strip, the same is provided with right angularly extending flanges 7 for bracing the ends of the strip. It will be obvious 70 that these retaining elements may be swung upon the screws 6 for holding the strips 4 at an angle whereby the hone A may be mounted upon the base at an angle for obtaining a greater bearing surface for the 75 edge of the razor blade while the same is being sharpened.

Mounted upon the extension 2 is a disk 8 having diametrically opposite flanges 9' through which fastening screws are extended for fastening the disk to the extension 2. 85 As clearly shown by Fig. 2 of the drawing, the disk 8 is raised above the plane of the base 1 to provide a space beneath the disk in which the flange 9 of a rotatable cylinder 10 is received. The cylinder 10 is projected 90 upwardly through the central opening in the disk and is open at its top. Oppositely disposed vertical slots are provided in the cylinder and the shank 11 of a spring clip 12 95 is disposed within the slots. The shank 11 is disposed within the slots. The shank 11 extends considerably beyond the cylinder and is provided at its terminal with a knob 13. The spring clip 12 consists of a cylindrical sleeve having a longitudinal slot 14 100 which communicates with a circumferentially extending slot 15 formed adjacent the point at which the clip joins the shank 11. By virtue of the slot 15, the edges of the clip are permitted to spring toward or away 105 from each other as the razor blade is thrust into the slot 14 or pulled out of the same thereby providing a gripping action that retains the razor blade in place so that it may be honed.

110 It will be noticed that the bottom of the cylinder 10 is closed while attached to the

wall of the closed end is a coil tension spring 16 which has its opposite end provided with a loop 17 which receives the shank 11.

After placing the razor blade in the clip 12, it is merely necessary to grasp the knob 13 and impart a reciprocatory movement to the shank 11, the cylinder 10 rotating and acting as a pivot for the clip. The spring, by virtue of its action on the shank 11, will 10 maintain an even pressure on the edge of the razor blade so that the operator need not press at all upon the knob 13. If desired the hone may be turned to a different angle to obtain a greater "sweep" for the blade. 15 By virtue of the loop around the shank 11 and the cylindrical formation of the clip the blade may be easily turned over so that both sides may be operated upon the surface of the hone.

From the foregoing it will be observed that a very simple and durable razor honing implement has been provided, the details of which embody the preferred form. I desire it to be understood however, that slight changes in the minor details of construction may be made without departing from the spirit of the invention or the scope of the claims hereunto appended.

I claim:

1. In a razor honing implement, the combination of a base having a hone mounted thereon, a rotatable cylinder also mounted in the base at one side of and intermediate the ends of the said hone, the said cylinder having vertically extending slots, a blade holding clip provided with a shank adapt-

ed to extend through the said slots, a resilient means arranged in the cylinder and fixed thereto and connected with the said shank for exerting a pressure downwardly 40 of the clip against the said hone.

2. A razor honing implement comprising the combination with a hone, of gripping means for receiving the razor blade and extending across the face of the hone, the 45 said means including a shank projecting beyond the edge of the hone, a rotatable cylinder provided with slots for receiving the said shank, and a coil spring mounted in the cylinder and including a loop encircling the 50 said shank, whereby the pressure of the clip on the said hone may be evenly maintained during the reciprocation of the clip.

3. A razor honing implement comprising, the combination with a razor hone, of a 55 base, a raised disk mounted upon the base and having a central opening, a rotatable cylinder extending through the opening in the raised disk and provided with an annular flange engaging the bottom of the said disk, a clip carried by the cylinder and engaged with the said razor, the said cylinder having slots, and the said clip including a shank received in the said slots, and a tension spring carried by the cylinder and fastened to the said shank.

In testimony whereof I affix my signature in presence of two witnesses.

ALFRED FRENETTE.
